CLAIM

The ornamental design for an adhesive backed target disc with hole, as shown and described.

DESCRIPTION

FIG. 1 is front view of the adhesive backed target disc with hole showing the claimed design;

FIG. 2 is a top view thereof;

FIG. 3 is a front perspective view thereof;

FIG. 4 is a rear view thereof;

FIG. 5 is a bottom view thereof;

FIG. 6 is a rear perspective view thereof;

FIG. 7 is a right side view thereof;

FIG. 8 is a left side view thereof; and,

FIG. 9 is a rear perspective view thereof with adhesive cover partially peeled back to expose adhesive, for clarity of illustration.

The broken lines in the drawings are for the purpose of illustrating environmental structure which form no part of the claimed design.

1 Claim, 3 Drawing Sheets
